HYDRAULIC CROWDER

Kirwan Messick, Clarendon, Va.

Application August 26, 1931. Serial No. 559,533

4 Claims. (Cl. 214—135)

The present invention relates to excavating machinery and more particularly to a hydraulic drive to be used in connection with the crowding or thrusting mechanism of said power excavators having among its principal objects to improve the power efficiency and operation, closely approaching steam for crowder drives, obviating the necessity for gearing, difficulties commonly experienced with steam driven crowders, as well as air driven crowders, in that there is no possibility of freezing of the fluid employed as is common in air driven crowders, when the machines are used in frigid regions.

Another object of the present invention is to provide an independent crowding mechanism for power driven excavators, which is solely carried by and mounted upon the boom of the excavator, independent, because it is not directly connected with the other driven mechanisms of the excavator and mounted upon and carried by the boom not only because of the saving of space within the cab of the excavator but because of the fact that a boom having any of the prevailing types of excavating implements carried thereby may be readily connected to the excavator whereby the excavating machine may be selectively converted into a trench hoe, skimmer-scoop, dipper bucket, or the like excavator, or it may be selectively converted into a pile driver, derrick, or crane.

A further object of the present invention is to provide a hydraulic drive system for excavating machines of the character heretofore mentioned which is so designed that the prime mover, whether it be an internal combustion engine, or an electric motor, need only be of such capacity as to carry the average load of the boom and shovel hoisting mechanism therefor, as at no time does the load of the crowding operation act directly upon the prime mover, thereby accomplishing the maximum amount of work with a minimum amount of power.

In the hydraulic drive system embodying the present invention, I provide a prime mover for driving a pump of the rotary type which latter, during its continuous operation, causes to be stored up in a suitable reservoir or tank, fluid, preferably oil, under pressure and the fluid so stored within this pressure tank is fed to a single or double acting hydraulic motor arranged upon the boom of the excavator and connected to the dipper stick thereof by means of wire ropes or cables. The opposite ends of these cables are affixed to the dipper stick and boom through suitable shock absorbers, thereby cushioning the

shock to the cables or ropes and their respective motors, when the thrusting or reversing action takes place. The prime mover also being through a suitable mechanical drive connection, is connected to the boom and shovel hoisting means so that when the crowding mechanism is in operation, the full power of the prime mover may be utilized for operating the boom or shovel hoisting mechanism. When the hoisting mechanism is at rest, the system is so arranged as to permit the prime mover to cause power to be stored up in the fluid pressure tank and, therefore, it is a still further object of the present invention to provide a control means for hydraulic drive systems for power operated excavators whereby the prime mover will be automatically disconnected from the hydraulic drive system when the hoisting mechanism is brought into play, and when the hoisting mechanism is at rest, the prime mover will be employed for storing up power which will be subsequently used for driving the crowder mechanism.

A rotary type of hydraulic pump is preferably employed in the present drive system, as it requires less horsepower to drive the same during the idling period than is required by piston type air compressors or pumps, therefore leaving a greater amount of horsepower generated by the prime mover to drive the boom or bucket hoisting mechanism.

My improved hydraulic drive system and the general assembly of an excavator to be herein-after described is comparatively inexpensive to build having but a reduced number of joints and power moving parts, such as shafts, gears, clutches, toggles, brakes, and the like, than is required by the mechanical drives now being extensively used. Due to the cable connections between the dipper stick and the crowder motors, the pistons of the latter will have a ratio operating movement of 2 to 1, that is, each piston will travel one foot for every two feet of travel of the dipper stick.

In order that the invention and its mode of operation may be readily understood by persons skilled in the art, I have, in the accompanying illustrative drawings and in the detailed following description based thereon, set out several possible embodiments of the same.

In these drawings:

Figure 1 is a fragmentary side elevation of a conventional form of power driven excavator having the improved hydraulic crowd mechanism embodying the present invention applied thereto;

Figure 2 is a detail view partly in section of one of the flexible connections between a cable of the hydraulic crowd mechanism and the dipper stick of the excavator;

5 Figure 3 is a diagrammatical showing of the hydraulic crowd mechanism embodying the invention;

10 Figure 4 is a side elevation of another form of excavator known as the skimmer-scoop having another form of my improved hydraulic thrusting 10 or crowding mechanism applied thereto,

15 Figure 5 is a detail sectional view of a control valve used in connection with my improved hydraulic crowd system and,

15 Figure 6 is a detail plan view of the cab showing the mechanical drive connection between the prime mover and the hoisting drums.

Referring now more particularly to the accompanying drawings wherein like corresponding parts are designated by similar reference characters throughout the several views, I have herein shown an excavator comprising a truck frame 1 mounted upon an appropriate creeping tractor mechanism 2 and rotatably mounted upon this truck frame 1 is a cab 3 provided with the usual platform 4. Hingedly connected to the forward end of this platform 4 is a boom 5 having mounted for reciprocal movement therein, a dipper stick 6 carrying at its lower end a dipper shovel 7. Arranged upon the platform 4 of the cab is a prime mover 8 which may be a gas engine, steam engine, electric motor, or any other source of motive power necessary for operating the shovel 7 of the excavator. Also arranged upon the platform 4 of the shaft is a drum 9 which is preferably driven by the prime mover 8 and over this drum there extends a cable 10 of the dipper hoisting mechanism. The cable 10 of this dipper hoist extends over the fair-lead sheaves 11 mounted upon the boom 5 and over another sheave 12 connected to the dipper 7 whereby with rotation of the drum 9, the shovel 7 may be raised or lowered. The boom hoist comprises a cable 13, one end of which is attached within the cab 3 and after extending over the sheave 14 secured to the outer end of the boom, the opposite end is attached to a winding drum 80, which latter is also propelled by the prime mover 8.

The thrusting or crowding mechanism comprises a motor preferably mounted upon the boom 5 and as this boom 5 is connected to the platform 4 of the cab through the detachable connection 15, many other types of excavating mechanism may be connected to this cab, one of which being shown in Figure 4 of the drawings and known as a skimmer-scoop. This independent hydraulically operated crowder for excavators being arranged upon the boom thereof not only permits the machine to be selectively converted into other types of excavators or cranes, but makes it possible to eliminate the mounting of complicated crowding mechanism within the cab of the truck or tractor, thereby giving considerably more space in the cab or permitting the reduction in size thereof, and this crowder being hydraulically operated, permits of the use of a prime mover of such capacity as is only necessary to store up the required fluid pressure due to the fact that the load carried through this crowder mechanism does not act directly on the prime mover.

The driven shaft 16 of the motor 8 is connected through the universal coupling 17 to the shaft 18 of a rotary pump 19 and this pump 19 has communicating with its inlet port, a pipe

line 20, and with its outlet port, a pipe 21. The fluid, preferably oil, is stored within the reservoir 22 and flows from this reservoir 22 to the pipe 20 in the pump. The fluid under pressure then passes through the pipe 21 by a check valve 23 to a high pressure reservoir or tank 24. A by-pass 25 establishes a means of communication between the pipe lines 20 and 21 around the pump 19 and has arranged therein a rotary valve 26 in order that when the valve 26 is opened and the pump 19 set in motion, the fluid from the storage tank 22 will be caused to circulate through this by-pass pipe 25, but when the valve 26 is closed, the pump will cause the fluid to pass through the pipe 21 into the pressure tank or reservoir 24.

For effecting the crowding movement of the dipper shovel 7, I preferably use two motors, one for causing the thrusting of the dipper within the work and the other for retracting the dipper from this work; however, it is to be understood that a single motor may be supplied which will cause the shovel and dipper stick to move in opposite directions. The thrusting motor 27 comprises a cylinder having a piston 28 mounted for reciprocation therein, whereas the retracting motor 29 comprises a cylinder of smaller diameter than that of the thrusting motor and having a piston 30 mounted for reciprocation therein. A fluid supply pipe 31 leads from the pressure tank 24 and has a hand valve 32 arranged therein. This supply pipe 31 leads to a control valve 33. A return pipe 34 leads from this control valve 33 and communicates with the storage tank 22. A pipe line 35 establishes a means of connection between the valve casing of the control valve 33 and one end of the cylinder 27, and a similar pipe line 36 establishes a means of communication between the control valve and one end of the cylinder 29. The opposite ends of these cylinders 27 and 29 are in communication with the return pipe 37 which latter leads to the storage tank 22 in order that any leakage that may occur within these cylinders 27 and 29 around their respective pistons, 120 may be caused to flow through this return pipe 37 and return to the storage tank 22. A rotary valve 38 is arranged within the valve casing of the hand operated valve 33 whereupon when this valve 38 is in the position as is shown in Figure 3 of the drawings, the fluid under pressure within the tank 24 may be permitted to pass through this valve 38 into the pipe line 35 leading to one end of the cylinder 27, whereby pressure may be supplied to the piston 28 arranged within this cylinder. When this valve 38 is in the position as herein shown, any liquid within the cylinder 29 will be forced by the return of the piston 30 through the pipe line 36 into the pipe line 34 and subsequently to the storage tank 22. From this, it is quite obvious that by rotating the valve 38 the fluid under pressure from the pressure tank 24 may be held against entering the pipes 34, 35 or 36, but when in another position, or that shown in Figure 3 of the drawings, this fluid under pressure may be supplied to the cylinder 27 and exhausted from the cylinder 29 and when this valve 38 is in a third position, the fluid under pressure may be supplied to the cylinder 29 and exhausted from the cylinder 27 where it may return from this cylinder 27 to the storage tank 22.

The pistons 28 and 30 mounted within the respective cylinders are each provided with a piston rod or stem 38 and connected to the out-

er end of each stem 38 is a crosshead 39 which latter are mounted for reciprocation within suitable guide-ways 40. The crosshead connected to the thrusting motor 27 carries a sheave 41 whereas a sheave 42 is carried by the crosshead connected to the retracting motor 29. A cable 43 has one end connected as at 44 to the cylinder 29 and after passing over the sheave 42 and one of the sheaves indicated by the numeral 45 arranged upon the boom has its opposite end fixed as at 46 to the lower end of the dipper stick 6. Another cable 47 has one end fixedly secured as at 48 to the cylinder 27 and after extending over the sheave 41 as well as another sheave 45 mounted upon the boom at its opposite end, attached to the upper end of the dipper stick 6 as at 49. The operator when positioned within the cab 3 may, through manipulation of the lever 50, control the valve 38 whereby the fluid under pressure may be supplied to and from the respective motors 27 and 29 for causing the thrusting or crowding of the shovel 7 to and from its work.

The opposite ends of the cables 43 or 27 are connected through a resilient connection or a shock absorber, as is better illustrated in Figure 2 of the drawings. This shock absorber comprises a bracket 51, one of which is herein shown as being attached to each cylinder of the motors 27 and 29 and upon the opposite ends of the dipper stick 6 and has mounted for reciprocation therein a rod 52. One end of this rod 52 is threaded and receives a lock nut 53 and arranged between the brackets 51 and these lock nuts is a coil spring 54. The opposite ends of the cables 43 and 47 of this crowding mechanism which for convenience, are indicated in Figure 2 of the drawings by the numeral 56, are connected to a rod 52 through the swivel connection 55, and it is through this connection that the cables 43 and 47 will, at all times, be held taut and at the same time, produce a cushioning effect upon each retracting or thrusting movement of the dipper stick.

It is sometimes only necessary to provide a single motor upon the boom of the excavator when the latter is converted into a skimmer-scoop such as that illustrated in Figure 4 of the drawings. In this latter figure of the drawings, the boom 5, together with its crowding mechanism and shovel, is removed and a boom 57 of a skimmer-scoop is connected to the platform 4. A scoop 58 is mounted for reciprocation upon this boom 57 and has connected thereto a cable 59 which latter extends over the sheaves 50 and 61 mounted upon this boom 57 whereby the scoop may be drawn towards the outer end of the boom. A boom hoisting cable 62 is connected to the outer end of the boom for raising the same and when this boom is in an elevated position, this scoop 58 will be permitted to travel by gravity towards the lower end of the boom. The single motor comprising a cylinder 63 is mounted upon the boom 57 and the piston rod thereof carries a sheave 64 over which passes this cable 59 and one end of the cable 59 is attached as at 65 to the cylinder 63. A valve casing 66 is provided within the cab having connections with the pipe lines 31 and 37 of the hydraulic power supply system, whereas another pipe line 67 establishes a means of communication between the valve casing 66 and one end of the cylinder 63. Another pipe line 68 establishes a means of communication between the opposite end of this cylinder 63 and the return pipe 37 whereupon should any leakage occur with-

in the cylinder 63 around the piston arranged therein, this fluid will be returned to the storage tank 22. A valve 69 is arranged within the casing 66 and is controllable through the lever 70 whereby the operator may by rotating this valve 69, permit the fluid under pressure in the pressure tank or reservoir 24 to pass into the cylinder 63 through the pipe line 67 or the fluid so spent within this cylinder 63 may be permitted to return through the pipes 67 and 37 to the storage tank 22. When the fluid under pressure is supplied to the cylinder 63, the piston and its sheave 64 will be thrust outwardly from this cylinder 63, whereby through the cable connection 59, the scoop 58 will be thrust towards the outer end of the boom 57.

In Figure 6 of the drawings, I have disclosed the mechanical drive connection between the prime mover 8 and the hoisting drums. These hoisting drums are mounted in a conventional manner upon a single driven shaft which latter is rotated through the medium of the chain and sprocket connection 84 by the motor 8. The shovel or dipper hoisting cable 10 is adapted to be wound upon the drum 9 whereas the boom 100 hoisting cable 13 is adapted to be wound upon the drum 80. Through the conventional form of clutches as herein indicated by the numerals 81 and 82, these drums 9 and 80 may be operatively connected to the driven shaft and these clutches 105 are adapted to be controlled by the operator through the usual foot levers 83. The valve 26 arranged within the by-pass 25 is provided with a lever 71 and the latter may be connected to the rod 72 to either of the hand levers 50 or 70 in 110 order that when either the valve 38 or 69 is open so as to permit the fluid under pressure to travel to either one of the cylinders 27, 29 or 63, the valve 26 will be closed in order that the fluid passing from the pump 19 may be delivered to 115 the reservoir 24 whereby the full power of the motor and that stored up within this reservoir 24 may be utilized for driving the hydraulic motors comprising the cylinder 27, 29 or 63. Through this arrangement, it is quite obvious that 120 when the excavator is at rest, the motor or other prime mover 8 will be continually storing up this fluid under pressure within the reservoir 24 and should the pressure within this tank 24 be greater than that desired, it may pass through the pipe 125 73 having a release valve therein to the storage tank 22. It will be obvious that the levers 50 or 70 which are arranged adjacent the driver's seat within the cab of the excavator will jointly control the valves 26 and 38 or 69 in order that when 130 the valve 26 is open the valve 38 or 69 will be closed and vice versa, in order that when the hoisting of the boom or shovel is required, the entire horsepower of the motor 8 may be utilized solely for this purpose, but when the boom 135 and shovel hoisting means are at rest, the motor, together with the pressure stored up within the tank 24 may be directly used for supplying hydraulic power to the motors of the crowd mechanism. Through the continual operation of the 140 motor 8, and when the crowding and hoisting mechanisms are at rest, the fluid under pressure is being continuously stored within the tank 24 thereby permitting the motor, at all times, to run at a constant speed without stopping and 145 starting the same as when the crowding or hoisting means are required for use.

From this arrangement, it will be further apparent that the prime mover need only be of such capacity as to carry the average load of the boom 150

and shovel hoisting means, therefore, as at no time does the load of the crowding operation act directly upon this prime mover, the horsepower of the latter may be greatly reduced over that required by the conventional type of power driven excavator. I have found that by using a prime mover of sufficient horsepower, at its maximum speed, will drive the hoisting means, will also have sufficient horsepower at its minimum speed or when idling, to operate the pump 19, thereby greatly increasing the saving of fuel consumed. The hydraulic rotary type of pump 19 as disclosed herein, from actual tests, has proven that it requires less horsepower than is required to drive the same during the idling period of the motor than would be required for driving the piston type air compressor or pump, thereby accomplishing a maximum amount of work with a minimum amount of power.

20 Manifestly, the construction herein shown is capable of considerable modification and such modifications as come within the scope of my claims, I consider within the spirit of my invention.

25 I claim:

1. A hydraulically operated crowding mechanism for excavators comprising in combination a boom, a dipper stick slidably mounted upon said boom, a pair of hydraulically operated motors arranged upon said boom, a pair of cables connecting said motors with the opposite ends of said dipper stick, and shock absorbers arranged between the opposite ends of said cables, said dipper stick and motors.

35. 2. An excavator comprising in combination a tractor, a power plant arranged upon said tractor, a boom detachably and hingedly connected to said tractor, a pair of hydraulically operated

motors arranged upon said boom, means whereby the power plant upon the tractor may supply fluid under pressure to said hydraulically operated motors, a dipper stick slidably mounted within said boom, shock absorbers fixedly connected to said dipper stick and motors, and cable connections between said dipper stick and motors whereby when said motors are operated said dipper stick will be caused to move in opposite directions upon said boom.

3. The combination with a boom of power driven excavators and a dipper stick mounted for reciprocation thereon, of a pair of hydraulically operable motors mounted directly upon said boom, cables connecting the opposite ends of said dipper stick with said motors whereby when the latter are set in motion, the dipper stick will be caused to reciprocate upon the boom.

4. A crowd mechanism for power driven excavators comprising in combination a boom, a dipper stick mounted for reciprocation within said boom, a scoop carried by one end of said dipper stick, a pair of hydraulically operable motors mounted directly upon said boom adjacent said dipper stick, each of said motors consisting of a cylinder having a reciprocating piston arranged therein, a piston rod carried by each piston, a sheave carried by each piston rod, a pair of cables, one end of each cable being connected to said dipper stick, the opposite ends of said cables being fixedly secured to the cylinders of said motors and said cables passing over said sheaves connected to the piston rods of said motors, whereby when the latter are set in motion, said dipper stick and the scoop carried thereby will be given a reciprocatory motion.

KIRWAN MESSICK.
